FURNACE ROOF CONSTRUCTION

William A. Vogt, 772 Moraga Road, Lafayette, Calif.

Filed May 26, 1958, Ser. No. 737,787

2 Claims. (Cl. 110—99)

This invention relates to industrial furnaces, and more particularly to furnaces of the open hearth type used in the refining of steel.

Since its inception, the open hearth furnace has been charged through spaced openings or doors in the front wall, this being necessary on account of the limitations imposed by the compromise between maximum furnace capacity and the absence of flexibility in presently utilized charging methods and equipment. This charging equipment comprises, heavy, cumbersome and relatively costly machines, which are not only slow and time consuming in their operation, but require an unduly large amount of plant floor space in which to function. The machines are inherently limited in their capacity, due to the restrictions imposed by the limited size of the door openings and the relatively small space in which they are required to operate. Due to these limitations, the number of charging boxes which must be handled during a charging operation is such that a great deal of time is consumed by the large number of charging machine operational cycles required.

While the time required to charge an open hearth furnace varies from one plant to another, on account of local facilities and individual furnace capacities, it is a matter of record that a modern open hearth furnace, of approximately 225 tons capacity, requires a charging time of from two to four hours.

Incidental to the fact that the charging operation extends over a relatively long period of time, is the further fact that the charging doors, in the front wall of the furnace, must of necessity remain open to accommodate this operation. It is obvious that these openings located as they are, below the level of the underside of the furnace roof, permit infiltration of cold air in such quantities as to lower considerably the thermal efficiency of the furnace. Also, the cooling effect of this air, impinging upon the furnace walls, is especially detrimental to the silica brick which forms part of the furnace lining, and definitely curtails the life of this refractory material.

The use of the presently accepted furnace charging equipment has influenced furnace design, the trend being toward a construction which would contribute to more efficient charging operations. While this is unquestionably a desirable advance with regard to charging simplification, unfortunately these changes have an adverse effect upon bath area, gas and air volume ratios, flame location, and, further, complicate furnace construction.

A closer approach to a more uniform placing or spreading of the charging material by presently accepted methods is not possible without unduly increasing the number of charging openings, in fact it has even been suggested that the entire side of the furnace should be removable. Of course, the tremendous heat loss involved, and the obvious structural problems which would be created by such a construction, render it entirely impractical.

While the foregoing disadvantages have long been apparent, up to the present time no practical solution has been made available either to appreciably simplify the

2

charging operation, or shorten the time necessary for its performance. It has been recognized that a furnace which could be charged through the roof would not only render the use of expensive and elaborate charging

5 equipment entirely unnecessary, but would afford a substantial reduction in the furnace charging time. With the use of large capacity, bottom dumping buckets, charging scrap, which constitutes approximately sixty percent of the charge, and with these buckets being handled 10 by a conventional overhead traveling crane, the charging time could be reduced to a maximum of approximately thirty minutes regardless of the furnace capacity, and the space presently required by the charging machines now in use could be utilized to better advantage.

A further advantage which would accrue from such an arrangement, resides in the fact that the air infiltration which now takes place while the charging openings are uncovered, would be entirely eliminated in a roof charged furnace, as no circulation would take place through the 20 top openings.

A furnace constructed with a plurality of longitudinally aligned openings in the roof would permit of a more uniform distribution of the charged material as each charge, being dropped vertically in a preselected and centrally disposed location, would spread out radially in all directions. This method of charging would preclude any advantages that may have existed in furnaces of asymmetrical cross-sectional configuration, and the departure from straight vertical walls with its attendant complicated construction would no longer be necessary.

More or less radical and unrealistic approaches to the foregoing have been made in an attempt to improve open hearth furnace operations. Suggestion has been made 25 for providing a roof which could be entirely removed for charging purposes. A further suggestion covers the

provision of a roof which being pivotally mounted along one edge could be swung upwardly and outwardly, simulating the action of a hinged cover or lid of a box. Obviously, the structural difficulties and mechanical 30 problems which would be encountered in an attempt to reduce these ideas to a practical basis can be considered as being unsurmountable. Also a means of controlling the enormous amount of heat which would be released by the removal of such roof construction would present 40 a problem the solution to which would be virtually impossible to attain.

It is the principal object of the present invention to provide a furnace with a greatly reduced charging time as compared to present day standards.

A further object of the invention is the provision of a furnace having a relatively high thermal efficiency.

Another object of the invention is the provision of a furnace which can be charged without the use of special equipment, and which will result in a more economical utilization of plant floor space.

55 Another object of the invention is the provision of a furnace which will permit of a more uniform distribution of charged material.

A still further object of the invention is the provision of a furnace which will be relatively easy to maintain.

60 These and other objects will become apparent during the course of the following description and appended claims, taken in connection with the accompanying drawing forming a part hereof.

On the drawing:

65 Figure 1 is fragmentary plan view of a preferred embodiment of my invention showing a typical charging opening.

Figure 2 is a longitudinal vertical cross section taken on line 2—2 of Figure 1 showing the cover in place.

70 Figure 3 is a transverse vertical cross section taken on line 3—3 of Figure 1 showing the cover in place.

Referring to the drawings in detail:

The roof of an open hearth furnace 10 is provided in spaced alignment, along a longitudinal median line, with a plurality of circular charging openings 11 communicating with the interior of the furnace F. The number of openings provided will be governed by the furnace hearth proportions, the relationship between the length and the width being of especial significance. Generally speaking, the portion of the hearth bath served by each opening will be substantially square in area, relative to a horizontal plane.

It will be noted that the roof 10 is of a sectionalized design and is a combination of substantially identical panels, the construction around each opening 11 following a similar pattern. Between each of the openings 11, and extending transversely across the furnace from wall to wall is a beam 12 which is a combination of sprung arch and suspended roof construction. The individual units 13 of the beam 12 are suspended in the conventional manner from a superstructure S as indicated by hanger rods 14.

The exterior sides 15 of the individual outer units 13 are formed in downwardly diverging relationship forming in effect, in longitudinal vertical section relative to the furnace proper, confronting faces of adjacent beams 12 which, acting as skewbacks, support the segments 16 of the polygonal structure 17 surrounding the opening 11. This method of construction will be clearly understood by reference to Figure 2.

The polygonal structure 17, which in the preferred embodiment is illustrated as being octagonal in form, will follow the general contour of the roof 11. The individual refractory units forming the sides of the polygonal structure are all formed with downwardly converging faces 18, as illustrated in section on Figures 2 and 3, and as further indicated by broken lines on the plan view Figure 1.

Except for the fact that all the bricks in the roof 10 which are contiguous with faces 18 have their contacting surfaces complimentary thereto, the remainder of the roof 10 follows the conventional pattern for this type of structure, the main arch being supported by skewbacks 19 held in place and stayed in the usual manner.

The circular opening 11 centrally located in the polygonal structure 17 has sides 20 which converge downwardly and are adapted to receive an annular member 21 having a depending skirt 22. This skirt has a tapered form complementary to the sides 20 of the opening 11, it will be apparent therefore, that when the depending skirt 22 of the annular member 21 is firmly set in place in the opening, the wedging action set up thereby, acting radially in all directions, will positively lock all of the

units forming the individual panels of the roof 10, firmly in place.

The annular member 21 is provided with an upper outstanding flange 23 having a concentric groove in its top side whereby a sand seal can be formed for the reception of a cover 24 as indicated on Figure 2. The annular member 21 is preferably cooled by means of circulated saturated steam, however, as this construction of cover, seal and cooling method follows conventional practice, it will not be further described herein.

From the foregoing it will be apparent that I have disclosed a novel method of roof construction which will make it possible to charge a furnace of the open hearth type through the roof. It will also be obvious that all the operations, ordinarily performed during the charging of the furnace, can be accomplished by standard overhead material handling equipment. While I have disclosed a preferred embodiment of my invention, it will be understood that modifications may be made within the spirit and scope of the appended claims.

I claim:

1. A furnace roof construction comprising a plurality of suspended transverse beams, said beams being in spaced and parallel relationship, the confronting faces of adjacent beams being adapted to form opposing skewbacks, a panel of bricks interposed in the space between each pair of adjacent beams and being supported thereby, said panel being of arcuate form relative to its transverse vertical cross-section, substantially straight relative to its longitudinal vertical cross-section and having its transverse edges sloping inwardly and downwardly complementary to the confronting faces of said beams, an annular member set into said panel and being adapted to form a charging opening therein, a depending skirt extending from said annular member, said skirt having its exterior surface converging toward its remote edge, the portion of said panel immediately surrounding said annular member being in wedging contact with said skirt and being of polygonal peripheral configuration.

2. A furnace roof construction as in claim 1 wherein the adjacent rows of bricks between said annular member and said transverse beams are sloped complementary thereto with reference to the vertical median plane transversely bisecting said panel, said adjacent rows of bricks being in corbeled relationship whereby the substantially straight longitudinal vertical cross-section is maintained.
